UNITED STATES PATENT OFFICE.

ARTHUR E. DOWELL, OF WASHINGTON, DISTRICT OF COLUMBIA, AND
WILLIAM B. MCHENRY, OF PITTSBURG, PENNSYLVANIA.

DRIER AND KILN.

SPECIFICATION forming part of Letters Patent No. 700,482, dated May 20, 1902.

Application filed July 6, 1901. Serial No. 67,313. (No model.)

To all whom it may concern:

Be it known that we, ARTHUR E. DOWELL, of Washington, District of Columbia, and WILLIAM B. MCHENRY, of Pittsburgh, Allegheny county, Pennsylvania, have invented certain new and useful Improvements in Driers and Kilns; and we hereby declare that the following is a full, clear, and exact description thereof, reference being had to the accompanying drawings, which form part of this specification.

This invention is an improvement in driers or kilns for drying lumber or for drying or burning brick, pottery, tile, &c., being especially designed, however, for drying purposes rather than for burning; and its object is to produce a simple and efficient drier which can be used with either an updraft or a down-draft, the invention having more particular reference to the portion of the apparatus whereby the downdraft is provided for. When used as a kiln, the products of combustion are admitted directly into the tunnels; but when used as a drier the products of combustion are excluded therefrom, but conducted through flues beneath the floor of the drier, so as to heat the several tunnels, and then conducted to the uptake, where they assist in creating a natural draft, whereby the moist vapors from the material being dried are drawn out of the tunnels.

The invention is summarized in the claims, and the accompanying drawings represent a drier embodying the improvements, which will be now described with reference thereto.

As shown, the general arrangement of furnaces, tunnels, smoke-flues, uptake, and up-draft-outlets is similar to that of the McHenry patented drier, No. 629,202, of July 18, 1899.

Figure 1 is a longitudinal sectional view through the complete drier, Fig. 2 being a transverse vertical section through the stack-end of drier on line 2 2, Fig. 1, Fig. 3 being a horizontal section on line 3 3, Fig. 2, and Fig. 4 is a detail.

The drier comprises one or more tunnels or drying-chambers A, each tunnel being practically alike and four being shown in the drawings, each extending longitudinally therethrough and closed by suitable doors at each end, as usual. At and below the discharge end of each tunnel is a furnace B, and the smoke is conducted therefrom when the ap-

paratus is used as a drier through a flue C, extending along and beneath the floor of the tunnel, so as to heat the latter, and at the inlet end of the tunnel this flue is turned off to one side and extends to the side of the drier and there connects with a vertical flue C', which leads up into the smoke-chamber E' at the base of the uptake E. The vertical flues C' are preferably extended inwardly above the outermost tunnels, as shown at C'', so as to create a stronger natural draft. Suitable air-heating passages and inlets D and D' may be arranged in the walls of the furnace and tunnels, as shown, so as to heat air and admit it into the tunnels at various points.

A direct outlet is provided for the vapors in the tunnels through openings f in the roofs thereof, at the receiving end of the drier, these openings being closable, when desired, by valves F, as shown. To increase the heat radiated into the tunnels, the roof of the flues or floors of the kilns may be partly formed of metal plates H, which are preferably located near the furnaces, as shown. If these plates are removed, the products of combustion can directly enter the tunnels, and the apparatus could then be used as a kiln; but ordinarily for drying purposes these plates are closely fitted in place, so that the products of combustion are excluded from the tunnels and only hot air admitted therein. The drier as thus far described is or may be practically constructed like the McHenry drier above referred to.

When valves F are opened, the vapors in the tunnels escape through openings f into the uptake by a direct or upward draft, and when thus used the drier operates as what is commonly termed an "updraft-drier." When it is to be used as a downdraft-drier, provision is made for removing the vapors from the receiving ends of the tunnels, at points at or near the floors thereof, as follows: In the walls of the tunnels, near the receiving ends thereof, are formed vertical vapor-flues G, which may be built like ordinary brick flues or may be formed of pipes or tubes of terra-cotta or other material built into the walls and partitions of the drier. Preferably these flues G extend up through the top of the tunnels into the smoke-chamber E' at the base of the uptake, as shown, and preferably the inner flues are continued up within this

smoke-chamber by the flue extensions $G' G^2$, as shown, and terminate a substantially uniform distance from the roof of the chamber, so as to equalize the draft in said flues. Thus 5 the innermost flues G are continued up within the smoke-chamber E' at the base of the uptake, as shown at G' , farther than the extensions G^2 of the next outermost flues, and the latter are longer or taller than the next 10 outermost flues, as shown. The outermost vapor-flues G in the outer walls of the kiln preferably open directly into the smoke-flues C^2 , as shown at g' , so that parts C^2 of the smoke-flues may also be used as continuations of 15 the outermost vapor-flues and assist in drawing the vapors out of the outer tunnels.

Preferably each tunnel is provided with two outlet-flues G , one at each side thereof, said flues opening at bottom into the tunnels, near 20 the floor thereof, as at g , so as to withdraw the vapors therefrom.

Preferably each flue G is distinct, so that 25 two tunnels do not directly communicate with a single vapor-flue. In some cases, however, it might be found practicable to let one vapor-flue communicate with two adjoining tunnels. It is considered preferable, however, to provide individual vapor-flues for each 30 tunnel. As the hottest smoke and vapors naturally pass along and near the top of the pent-roof e of the smoke-chamber E' , the advantage of extending the vapor-flues G through the lower part of this chamber, as shown at $G' G^2$, &c., is obvious, as the hot 35 currents of smoke passing the tops of the flues tend to create suction therein.

The openings g may be provided with valves, if desired, as indicated at g^3 , Fig. 4; but when 40 valves F are open the lighter vapors will naturally pass directly upward therethrough, and if any heavier vapors then pass out of the flues G the operation of drying will be facilitated, and when valves F are closed the vapors must pass out of the flues G . In some 45 constructions, if desired, the direct updraft-outlets could be made by providing openings g^3 (see Fig. 4) in the flues G near the tops of the tunnels, said openings being closable by valve g^4 ; but this is not considered a preferable 50 construction.

When valves F are closed, the moist vapors are forced down to the bottoms of the tunnels and pass into flues G through openings g and thence upward directly to the uptake in the most natural manner without having to follow any tortuous channels, and as the vapor-flues G are always entirely surrounded by heat they are therefore always in the best condition for creating a natural 55 draft upward draft in flues G , which causes a downdraft in the tunnels by exhausting vapors therefrom at points near the bottoms thereof. By this arrangement of vertical flues for creating the downdraft within the 60 body of the drier heat is economized as compared with downdraft arrangements employing long and tortuous underground flues, 65

every bend in which retards its drawing qualities.

Having thus described our invention, what 70 we therefore claim as new, and desire to secure by Letters Patent thereon, is—

1. The combination in a drier, of a series of tunnels, an uptake at one end of the drier, and means for heating the tunnels; with vapor-flues in the side walls of the several tunnels, opening at bottom into the bottom of the tunnels, and at top into the uptake, substantially as described.

2. The combination in a drier, of a series of 80 tunnels, an uptake at one end of the drier, and means for heating the tunnels and up-draft-outlets to the uptake; with downdraft vapor-flues in the opposite side walls of each one of the tunnels opening at bottom into the 85 bottom of the tunnels, and at top into the uptake, substantially as described.

3. The combination in a drier, of a series of tunnels, an uptake at one end thereof, and valved updraft-outlets connecting the tunnels with the uptake; with downdraft-flues in the walls and partition between each one of the tunnels communicating at their lower ends with the bottoms of the tunnels and at their upper ends with the uptake, substantially as described.

4. The combination in a drier, of a series of tunnels, an uptake at one end thereof, valved openings connecting the tops of tunnels directly with the uptake, and means for heating the tunnels; with vertical flues in the sides walls of each one of the tunnels communicating at their lower ends with the bottoms of the tunnels and at their upper ends with the uptake, substantially as described.

5. The combination of a series of tunnels 105 an uptake at one end thereof, having a smoke-chamber extending over the tunnels, and means for heating the tunnels; with down-draft vapor-flues in the partitions between the tunnels below the uptake, said flues communicating at bottom with the bottoms of the tunnels and extending up into the smoke-chamber, for the purpose and substantially as described.

6. The combination of a series of tunnels, an uptake at one end thereof having a smoke-chamber extending over the tunnels, valved openings directly connecting the tops of tunnels with the uptake, and means for heating the tunnels; with vertical vapor-flues in the walls and partitions between each one of the tunnels below the uptake, said flues communicating at bottom with the bottoms of the tunnels and extending up into the smoke-chamber, for the purpose and substantially as described.

7. In a drier, the combination of a series of 110 drying-tunnels, an uptake at one end thereof, and vertical flues in the opposite side walls of each one of the tunnels communicating at top with the uptake and at bottom with the lower portions of the tunnels.

8. In a drier, the combination of a tunnel,

- a furnace at the discharge end thereof, an uptake at the receiving end thereof and smoke-flues under the tunnel extended to and communicating with the uptake; with opposite vertical flues extending through the vertical division-walls of the tunnel at the receiving end of the drier communicating at their lower ends directly with the lower part of the tunnel, and at top with the uptake, substantially as described. 5
9. The combination of a series of tunnels, furnaces at one end thereof, an uptake at the other end thereof, and smoke-flues leading from the furnaces to the uptake; with flues 15 extending through the walls and partitions of the tunnels at the uptake end of the tunnel, communicating at bottom with the bottoms of the tunnels and at top with the uptake, substantially as described. 15
10. The combination of a tunnel, a furnace at one end thereof, an uptake at the other end thereof, and a smoke-flue exterior to the tunnel leading from the furnace to the uptake, and an outlet from the top of the tunnel to 25 the uptake; with vertical flues in the opposite side walls of the tunnel communicating at their lower ends directly with the tunnel near the floor thereof, and at top with the uptake, substantially as described. 25
11. In a drier the combination of a series of drying-tunnels, an uptake at one end thereof, openings directly connecting the top of the tunnels with the uptake, and vertical flues in the partitions between the tunnels communicating at top with the uptake, and at bottom with the lower portions of the tunnels. 30
12. In a drier, the combination of a series of tunnels, furnaces at the discharge end thereof, an uptake at the receiving end thereof, 40 openings connecting the top of the tunnels with the uptake, and smoke-flues under the tunnels and extended to and communicating with the uptake; with vertical flues extending through the partitions between the tunnels at the receiving end of the drier communicating at bottom with the lower parts of the tunnels, and at top with the uptake, substantially as described. 45
13. The combination of a series of tunnels, furnaces at one end thereof, an uptake at the other end thereof, an opening connecting the top of the tunnels with the uptake, and smoke-flues exterior to the tunnels leading from the furnaces to the uptake; with vertical flues 55 located therein the walls and partitions of the tunnels at the uptake end of the tunnels, communicating at bottom with the bottoms of the tunnels and at top with the uptake, substantially as described. 60
14. The combination of a series of tunnels an uptake at one end thereof having a smoke-chamber extending thereover, and furnaces at the other end thereof, and flues leading under the tunnels from the furnaces and connecting with the smoke-chamber by exterior flues; with vapor-flues in the side walls of 65 each one of the tunnels below the smoke-chamber communicating at bottom with the bottoms of the tunnels, and extending up into the smoke-chamber, substantially as and for the purpose described. 70
15. The combination of a series of tunnels, an uptake at one end thereof having a smoke-chamber extending thereover, and vertical smoke-flues at the sides of the tunnel communicating with the uptake by extensions at their upper ends; furnaces at and below the other ends of the tunnels, and smoke-flues leading from said furnaces beneath the tunnels and connecting with said vertical smoke-flues; with vapor-flues in the walls of partitions between the tunnels having their lower ends opening into the bottoms of the tunnels, and their upper ends extended upwardly into and communicating with the smoke-chamber, 80 substantially as described. 85
16. The combination of a series of tunnels, an uptake at one end thereof having a smoke-chamber extending thereover, and furnaces at the other end thereof, and flues leading 90 under the tunnels from the furnaces and connecting with the smoke-chamber by exterior flues, and valved openings in the roofs of the tunnels directly connecting the latter with the smoke-chamber; with vertical vapor-flues 95 in the walls of and partitions between the tunnels below the smoke-chamber communicating at bottom with the bottoms of the tunnels, and extending up into the smoke-chamber, for the purpose and substantially as described. 100
17. The combination of a series of tunnels, an uptake at one end thereof, having a smoke-chamber extending thereover, and vertical smoke-flues at the sides of the tunnel communicating with the uptake by extensions at their upper ends projecting into the smoke-chamber; furnaces at and below the other ends of the tunnels, and smoke-flues leading from said furnaces beneath the tunnels and 105 connecting with said vertical smoke-flues; with valved openings in the roofs of the tunnels to allow updraft of vapors into the smoke-chamber, and vertical vapor-flues in the walls of and between the tunnels having their lower 110 ends opening directly into the tunnels near the floors thereof, and their upper ends extended upwardly into and communicating with the smoke-chamber; substantially as described. 115
